RAILWAY TRUCK

Donald S. Barrows, Rochester, N. Y., assignor to
The Symington-Gould Corporation, Depew,
N. Y., a corporation of Maryland

Application January 3, 1947, Serial No. 720,068

31 Claims. (Cl. 105—197)

1

This invention pertains to a railway truck and more particularly to the structure in or adjacent to the window opening of a side frame thereof.

An object of the invention is the provision, in an improved railway truck, of a bolster movable vertically and transversely relative to a side frame with both of said movements snubbed by friction means.

Another object of the invention is the provision, in a railway truck, of a chair and side frame arrangement capable of rocking relative to a bolster supported thereby.

A further object of the invention is the provision, in a railway truck, of a bolster supporting plate arranged to move vertically and transversely of the truck and carrying friction means to frictionally engage a side frame during a vertical movement and to be frictionally engaged thereby during a transverse movement.

The above and numerous other as well as more detailed objects of the invention will become apparent upon a review of the succeeding description and the accompanying drawings, wherein:

Figure 1 is a partial front elevational and partial vertical sectional view of a railway truck embodying a form of the present invention.

Figure 2 is a partial plan and partial horizontal sectional view taken along the lines 2—2 of Figure 1, looking in the direction of the arrows.

Figure 3 is a transverse and vertical sectional view taken along the lines 3—3 of Figure 1, looking in the direction of the arrows.

Figure 4 is a vertical sectional view taken along the lines 4—4 of Figure 1, looking in the direction of the arrows.

Referring now in detail to the various figures of the drawings, wherein like reference characters indicate like parts, the numeral 1 is employed, in a somewhat general manner, to indicate a railway truck, preferably of the four wheel type. Only a portion at or adjacent to a center and one side of the truck is illustrated since the undisclosed portion is of no present moment and may, if desired, be of conventional form.

The railway truck comprises a side frame 2, only a central area of which is shown since it will be understood by those skilled in the art to which this invention pertains that a railway truck of the class herein considered comprises two side frames, one at each side of the truck, forming structural members for connecting integral or separate journal boxes (not shown) and transmitting loads thereto. The side frame comprises a top or compression member 3 spaced vertically

from a lower or tension member 4 both of which are joined intermediate their ends by longitudinally spaced, vertically extending columns 5 to present or define a window opening 6 therebetween. The compression member is somewhat conventional in transverse section in that it comprises a top web 3a having laterally spaced flanges 3b depending therefrom. The lower free edges of the flanges are joined by connecting a rib 3c. The tension member is also of somewhat conventional form in that its central horizontal portion comprises an upper web or bottom spring seat forming member 4a extended laterally of the side frame beyond the normal limits thereof to present an adequate bearing area for the accommodation of a nest of coil springs 7 (shown diagrammatically). Spaced a suitable distance below the spring seat forming member is a lower web 4b of less horizontal extent than its companion upper web and joined thereto by suitable side flanges 4c. The central portion of the tension member extends horizontally substantially between the columns from which locations they are directed upwardly as at 4d where, conventionally, they join (not shown) with the compression member. Also characteristically of some types of side frames the bottom spring seat forming member has, upstanding from lateral edges thereof, reinforcing flanges 4e which extend along the central horizontal portion to merge with the columns and upwardly directed parts 4d. Finally, so far as the tension member is concerned, it will be observed that the upwardly directed parts are of double truss design with the top trusses 4g thereof cutting diagonally across the lower corners of the window opening to merge with the bottom spring seat member at a spaced location removed from the related columns (see Figure 1).

Each guide column comprises a vertical transverse web 5a which at its upper end blends into compression member ribs 3c and its lower end merges with the top truss 4g of the tension member. Each column transverse web has outstanding therefrom transversely spaced flanges 5b directed longitudinally of the truck toward a related end thereof and merging at its respective upper and lower ends with the compression member flanges and tension member top truss as clearly indicated in Figure 1 of the drawings.

As previously stated, the central portion of the tension member functions additionally as a supporting area for a nest or group of conventional coil springs indicated diagrammatically as at 7. The group of springs function as a

2

yieldable support for a bolster 8, the latter of which extends between the related side frames as a load transmitting member and has an end 9 thereof disposed within the side frame window or opening 6. As will be appreciated, the truck proceeding along supporting rails will have its wheels passing over contiguous ends of rails, cross overs, switches, etc., which will cause the wheels to move vertically because of the differences in elevations of supporting surfaces at these locations. Also it may be observed that road beds are somewhat yieldable in character and thus a very slight vertical weaving action will be imparted to supporting rails as the truck passes thereover or therealong. Because of these recognized irregularities in the supporting rails the respective side frames of the truck will execute an action or motion akin to that of a hobby horse or rocking chair. In order to prevent the transmission of the natural hobby horse action of the side frame to the bolster it is to be here noted that the bolster is made up as a composite structure comprising, generally, a main bolster member 8 and an equalizing member, end plate, top spring plate or chair 10 positioned below and preferably in direct supporting relation with each bolster extremity 9.

The chair is arranged within the window opening and has a main plate or web 11 disposed substantially horizontally and positioned intermediate the height of the chair. A lower face or surface 12 of the web bears upon the subjacent nest of springs and extending downwardly from the web are laterally spaced vertical flanges 13 which reinforce the chair and prevent an unwarranted or accidental transverse displacement of the upper extremities of the springs forming the nest. The upwardly facing portion of the web is formed in part by a concave, cylindrical or arcuate, cradle forming surface 14 which terminates short of the horizontal limits of the web and is disposed in a substantially centralized position with the radius of curvature lying on a medial line or in a transverse vertical plane of the truck as indicated by the diagrammatic line "A—A" and as shown only in Figure 1 of the drawings. A bottom wall 15 of the bolster end is also provided with a cylindrical, curved or arcuate surface 16 but this latter surface is convex in character and desirably of a radius different than, but preferably shorter than that of the plate surface 14. The surface 16 is struck from the same medial line "A—A" and thus only a limited area of the bearing, arcuate surfaces 14 and 16 will be in engagement with one another and when the components of the truck are in their normal or illustrated positions this limited area of contact will be at or adjacent to the transverse medial line of the truck to allow the side frame and other components, inclusive of the chairs to rock in either directions and freely beneath a bolster end without imparting any of such movements to the bolster proper.

Means has been incorporated in the composite bolster structure to maintain the related components in a predetermined relationship and thus prevent a shifting action of one arcuate surface relative to another arcuate surface. In other words, aside from a desired relative rocking movement between the bolster proper and chairs it is preferred to have these elements move vertically and transversely in unison as a single or unitary bolster structure, for, among other reasons quite apparent, to assure a proper disposition of the cylindrical surfaces 14 and 16. Toward the accomplishment of the above the chair inter-

mediate web is provided with a series of outer teeth 17 disposed in series or alignment longitudinally of the truck and positioned outwardly of the truck from but adjacent to the concave surface. The outer teeth are arranged as a segment of a gear and accordingly have the pitch circle thereof coincident with the related concave surface. The bottom wall 15 of the bolster is provided with a series of downwardly extending, outer teeth 18 also arranged as a segment of a gear and having a pitch circle coincident with the related bolster convex surface 16 and being arranged to mesh with the chair outer teeth. Disposed inwardly of the truck from but adjacent to the chair concave surface is a second or inner row of teeth 17a extending upwardly from the chair web and formed as counterparts of the chair outer teeth. To facilitate the manufacture of the bolster the bottom wall thereof adjacent to the inner limits of the convex surface is indented or recessed as at 19. A separate segment of a gear 20 is disposed within the recess and is welded or otherwise secured to the bolster bottom wall. The gear segment 20 has downwardly extending inner teeth 21 meshing with the chair inner teeth and are substantially counterparts of the bolster outer teeth. It will be noted therefore that the intermeshing bolster and chair teeth maintain the cylindrical surfaces in a predetermined or fixed relationship and also prevent the bolster from assuming a horizontal angular position relative to its supporting associated chairs. Studs or posts 22 upstand from the chair through suitable apertures in the bolster bottom wall with keys or cotters 23 passing through the posts within the bolster. This construction prevents an accidental separation of the components forming the composite bolster structure.

From the description hereinabove set forth of the illustrated exemplification of the invention it will be noted that the arrangement forms a quick wheel change truck. In this regard it is to be noted further that upon a removal of the cotters 23 the bolster proper is elevated to a position where the bottom wall of the bolster clears the posts 22 and thereafter the side frame may be moved laterally away from the bolster end 9.

Since it is preferred to employ a group of all coil springs for the support of the composite bolster structure for reasons which are obvious, snubbing or friction creating means are incorporated in the truck structure to control or dampen out vibratory actions of the group. With this thought in mind each column is provided with transversely spaced, auxiliary flanges 24 which are vertically directed and extend in a direction toward the transverse medial line of the truck. These auxiliary flanges are formed integrally with the column webs in substantial alignment with their companion flanges 5b and the auxiliary flanges on each column are inclined or sloped transversely or longitudinally of the truck. This auxiliary flange arrangement, the reason for which will be hereinafter made apparent, presents a tapered or somewhat bell-mouthed housing exposed toward the center of the side frame and communicating with the bolster or window opening. So as to reinforce the auxiliary flanges against stresses to which they will be subjected in service, each auxiliary flange, which it might be here noted extends vertically for only a lower part of the full height of a related column, has its free end or edge provided with a vertically extending, terminal web 25 directed transversely and outwardly of the side frame. The terminal

5

web of each auxiliary flange merges at its lower extremity into the tension member while at its upper extremity it extends across the column flanges 5b to be formed integral with a related auxiliary flange. The longitudinal ends of the chair web 11 are formed integrally with vertical end walls 28 which extend transversely of the truck beyond the horizontal limits of the terminal webs of each column. Since the composite bolster structure is supported solely by the nest of all coil springs and due to the inherent flexibility of coil springs the side frame is permitted to execute a lateral motion relative to the composite bolster structure. This somewhat flexible connection between the bolster structure and side frame is preferred in the instant embodiment of the invention so that any lateral impulses imparted to the side frame during service movements thereof will not be transmitted to the bolster.

Confined within each housing defined by a column web, column auxiliary flanges and chair end wall are a plurality, preferably a pair of counter-part shoes 29 each having a longitudinally diagonal and vertically extending rubbing surface 30 maintained, at all times, in intimate contact with a correspondingly disposed rubbing surface 31 carried by the adjacent column auxiliary flange. The shoes of each pair are urged apart transversely of the truck by any type of compressible or resilient means which, in the instant structure, is characterized by a single coil or helical compression spring 32. Vertically spaced transversely and horizontally extending arms 33 are formed on each shoe with the arms having angularly disposed fingers 34 at their terminals. The fingers of related shoes are spaced from one another so as to allow a breathing action of the shoes and more particularly to prevent the friction means, inclusive of the shoes and interposed spring from exploding upon the removal thereof from the side frame. Each arm side wall has outstanding therefrom vertically spaced shelves or ledges 35 formed integral therewith and extending horizontally into a related column with adequate space of clearance thereabout so as to not interfere with the column. The chair shelves have surfaces 36 facing one another and arranged to contact crowned or convex surfaces 37 on the shoe arms thereby being arranged to move the shoes vertically during any service flexures of the spring group and also allow a transverse or tilting action of the side frame and friction means without disturbing the normal transverse position of the bolster and its supporting chairs. Any movement of the chair in a vertical direction will, therefore, be reflected in a corresponding movement of the friction shoes and a relative movement of the rubbing surfaces 30 and 31 the latter of which will snub, check or dampen out vibratory actions of the spring nest.

As noted by referring particularly to Figure 4 of the drawings, the helical compression spring 32 is so arranged or disposed that its axis extends diagonally and transversely of the truck with its ends bearing against normally positioned spring seats 38. Such a disposition of the helical compression spring results in the shoes of a pair being urged vertically in opposite directions to result in one shoe being pressed upwardly against a related shelf and the companion shoe being urged downwardly against a related shelf to prevent the shoes and shelves from setting up any chattering during service movements thereof.

As previously set forth there are, in the bolster-

5 side frame connection, provisions for relative transverse movements therebetween and in order to check or control these movements each side wall of the chair carries an outwardly exposed brushing surface 39 which extends vertically and transversely of the truck. Due to the particular disposition of the rubbing surfaces, the shoes will be urged outwardly of the columns and accordingly each shoe carries an outwardly exposed plane surface 40 arranged to bear against a related brushing surface so that frictional forces will be created thereon during any relative transverse or tilting movements of the side frame and chair or bolster.

10 In order to partially shield the friction means against the entrance thereto of dirt or other abrasive particles each bolster side wall 41 is provided with an outstanding hood-like member 42 made up of a top wall 43 overlying the friction means in vertical spaced relation thereto and extending longitudinally of the truck toward the related column web but terminating short thereof to allow for normal service movements of the bolster proper. Each top wall extends transversely of the truck a predetermined distance where it merges with a related vertically directed end wall 44.

15 From the above it will be noted that various changes and alterations may be made to the illustrated form of the invention without departing from the spirit of the invention and scope of the appended claims.

I claim:

20 1. A railway truck comprising in combination with a side frame having columns defining a window opening with a bolster end positioned in the opening, a nest of springs carried by said side frame within said opening, a chair mounted on said nest of springs and having vertically spaced ledges extending into said columns, vertical surfaces carried by said chair, friction means movable vertically by said ledges and arranged to engage frictionally said columns and chair vertical surfaces, and engaging rocker surfaces carried by said bolster and chair.

25 2. In a railway truck wherein a side frame is provided with a window opening defined by columns and a bolster end is positioned within the opening, the combination of, a spring supported chair within said opening and having vertically spaced flanges extending into said columns, friction means movable vertically by said chair flanges for frictionally engaging said columns, and contacting arcuate surfaces of different radii on said bolster and chair for allowing said chair to rock longitudinally of said truck beneath said bolster.

30 3. In a railway truck wherein a side frame is provided with a window opening defined by columns and a bolster end is positioned within the opening, the combination of, a spring supported chair within said opening and having vertically spaced ledges extending into said columns, said chair being arranged to move vertically and transversely of said side frame, friction means within said columns and movable vertically by said chair shelves, said friction means being so arranged and constructed as to frictionally engage said columns and chair for snubbing both vertical and transverse movements of said chair, and contacting arcuate surfaces of different radii on said bolster and chair for allowing a relative rocking action between said bolster and chair.

35 4. In a railway truck wherein a side frame is provided with a window opening defined by col-

umns and a bolster end is positioned within the opening, the combination of, a spring supported chair within said opening and having vertically spaced longitudinally extending shelves disposed in said columns, vertical surfaces on said chair within said opening, transversely spreadable friction means disposed between and movable vertically by said shelves, said chair being movable vertically and transversely relative to said side frame, said friction means being so arranged and constructed as to frictionally engage said columns and chair vertical surfaces for snubbing all of said movements of said chair, and engaging arcuate surfaces on said chair and bolster for allowing a rocking action between said bolster and chair.

5. In a railway truck wherein a side frame is provided with a window opening defined by columns and a bolster end is positioned within the opening, the combination of, a spring supported chair within said opening, vertically spaced shelves on said chair and extending into said columns, transversely spreadable friction means within said columns and movable vertically by said shelves for frictionally engaging said columns, inclined surfaces on said columns and friction means for directing said friction means toward said opening into engagement with said chair, and arcuate surfaces of different radii on said bolster and chair for allowing a relative 30 rocking motion between said chair and bolster.

6. In a railway truck wherein a side frame is provided with a window opening defined by columns and a bolster end is positioned within the opening, the combination of, a spring supported chair within said opening and carrying said bolster end, outstanding ledges at the vertical limits of said chair and extending into said columns, friction means spreadable transversely of said truck into engagement with said columns, 40 said friction means being movable vertically by said chair ledges, a concave surface on said chair, and a bolster carried convex surface of different radius than and bearing upon said chair concave surface.

7. In a railway truck wherein a side frame is provided with a window opening defined by columns and a bolster end is positioned within the opening, the combination of, a spring supported chair within said opening and carrying said bolster end, substantially parallel outstanding ledges at the vertical limits of said chair, friction means within said columns and spreadable transversely into frictional engagement with said columns, said friction means being movable vertically by said ledges, a concave surface on said chair intermediate the height thereof, and a bolster associated convex surface of different curvature than and bearing upon said chair concave surface.

8. In a railway truck wherein a side frame is provided with a window opening defined by columns and a bolster end is positioned within the opening, the combination of, a spring supported chair within said opening and supporting said bolster end, substantially parallel outstanding ledges at the vertical limits of said chair and extending into said columns, substantially vertical surfaces carried by said chair between said ledges, said chair being arranged to move vertically and transversely relative to said side frame, and friction means movable vertically by said chair ledges; said friction means being arranged to engage said columns and chair surfaces for snubbing all of said chair movements.

9. In a railway truck wherein a side frame is provided with a window opening defined by columns and a bolster end is positioned within the opening, the combination of, a spring supported chair within said opening and supporting said bolster end, substantially parallel outstanding ledges adjacent the vertical limits of said chair and extending into said columns, substantially vertical surfaces carried by said chair between said ledges, said chair being arranged to move vertically and transversely relative to said side frame, friction shoes spring pressed transversely and movable vertically by said chair ledges, said shoes being arranged to engage frictionally said columns and chair surfaces for snubbing relative movements between said chair and side frame, and means on said chair for limiting said chair transverse movements.

10. In a railway truck wherein a side frame is provided with a window opening defined by columns and a bolster end is positioned within the opening, the combination of, a spring supported chair within said opening, substantially parallel outstanding ledges adjacent the vertical limits of said chair and extending into said columns, friction shoes movable vertically by said ledges and spring pressed transversely into frictional engagement with said columns, a cylindrically disposed surface on said chair intermediate the height thereof, a cylindrically disposed surface on said bolster bearing upon and of different curvature than said chair cylindrically disposed surface, and means on said chair and bolster for preventing relative horizontal angular movement therebetween.

11. In a railway truck wherein a side frame is provided with a window opening defined by columns and a bolster end is positioned within the opening, the combination of, a spring supported chair within said opening and having spaced transverse vertical surfaces adjacent said columns, said chair being arranged to move transversely relative to said side frame, vertically spaced ledges extending into said columns from adjacent the vertical limits of said vertical surfaces, spring pressed shoes within said columns movable vertically by said ledges and arranged to engage frictionally said columns and chair surfaces, an arcuate surface intermediate the height of said chair, and an arcuate surface on said bolster in engagement with said chair arcuate surface.

12. In a railway truck wherein a side frame is provided with a window opening defined by columns and a bolster end is positioned within the opening, the combination of, a spring supported chair within said opening, said chair being arranged to move transversely and vertically relative to said side frame, vertically spaced ledges extending into said columns from said chair, spring pressed shoes within said columns and between said ledges and arranged to be moved vertically by said ledges, said columns and shoes being arranged to direct said shoes into intimate contact with said columns and toward said opening against said chair for snubbing both of said chair movements, rocker means formed on said chair and bolster, and interlocking means formed on said chair and bolster for holding said rocker means in a predetermined relationship.

13. In a chair for use between columns of a side frame, the combination of, a web disposed intermediate the height of said chair, vertical end friction walls spaced apart and extending above 75 and below said web and arranged to be positioned

adjacent to said columns, vertically spaced substantially horizontal ledges outstanding from each end wall and arranged to extend into said columns, and a rack formed on said web.

14. In a chair for use between columns of a side frame, the combination of, a web disposed intermediate the height of said chair, an upwardly facing concave surface on said web, vertical end walls spaced apart and extending above and below said web and arranged to be positioned adjacent to said columns, each wall having vertically spaced substantially horizontal ledges outstanding from adjacent the vertical limits of said wall in a direction away from said web, and a rack adjacent said concave surface.

15. In a chair for use between columns of a side frame, the combination of, a web disposed intermediate the height of said chair, vertically disposed end friction walls spaced apart and extending above and below said web and arranged to be positioned between and adjacent to said columns, a friction surface carried by said end walls for constant engagement by a friction means, and vertically spaced substantially horizontal ledges outstanding from said side walls in a direction away from said web.

16. In a chair for use between columns of a side frame, the combination of, a web disposed intermediate the height of said chair and having a downwardly facing spring seat and upwardly facing bolster seat, vertical walls on said web at sides thereof and extending above and below said seats, outwardly facing surfaces on said walls for constant engagement by friction means, and vertically spaced friction means engaging ledges outstanding from each wall.

17. In a railway truck wherein a side frame is provided with a window opening and a bolster end is positioned within the opening, the combination of, columns in said side frame having portions extending inwardly of and outwardly from said window opening, said columns having intermediate webs between said portions and extending transversely of said truck beyond said portions, a top spring plate within said opening arranged to move vertically and transversely of said side frame, friction means within and engaging said inwardly extending column portions and said top spring plate, means on said top spring plate for moving said friction means upwardly and downwardly, and hood means on said bolster overlying said friction means and inwardly extending column portions.

18. In a railway truck wherein a side frame is provided with a window opening defined by columns and a bolster end is positioned within the opening, the combination of, a spring supported top plate within said opening and directly supporting said bolster, horizontal ledges outstanding from said top plate and extending into said columns, shoes within said columns and movable upwardly and downwardly by said ledges, and diagonally disposed spring means urging said shoes transversely of said truck into frictional engagement with said columns.

19. In a railway truck wherein a side frame is provided with a window opening defined by columns and a bolster end is positioned within the opening, the combination of, a spring supported top plate within said opening, said top plate normally contacting said bolster adjacent a transverse medial line only of said truck, shelves outstanding into said columns from said top plate above and below said bolster-top plate contact,

interlocked friction shoes within each column and being movable upwardly and downwardly by said shelves, and spring means disposed diagonally and urging said shoes into frictional engagement with said columns.

20. In a railway truck wherein a side frame is provided with a window opening defined by columns and a bolster end is positioned within the opening, the combination of, a spring supported top plate within said opening, said top plate normally contacting said bolster adjacent a transverse medial line only of said truck, shelves outstanding into said columns from said top plate above and below said bolster-top plate contact, said top plate being arranged to move vertically and transversely of said truck, outwardly exposed surfaces on said top plate adjacent said columns, interlocked friction shoes within each column and movable vertically by said shelves, spring means acting against said shoes for urging them into frictional engagement with said columns and top plate surfaces to snub all movements of said top plate, and means connecting said bolster and top plate thereby causing said bolster and top plate to move vertically and horizontally in unison.

21. A railway truck comprising in combination with a side frame having columns defining a window opening with a bolster end positioned in said opening, a nest of springs carried by said side frame within said opening, a chair mounted on said nest of springs and having vertically spaced ledges extending into said columns, friction means carried by said ledges and arranged to frictionally engage said columns and chair intermediate said ledges, contacting rocker surfaces on said bolster and chair, and interlocking teeth on said bolster and chair for preventing angular relative displacement between said bolster and chair.

22. In a bolster having an end arranged to extend into a window opening of a side frame, the combination of, a lower convex surface on said bolster end, racks arranged on an arc at each side of said convex surface, and hoods outstanding from sides of said bolster end.

23. In a bolster having an end arranged to extend into a window opening of a side frame, the combination of, a lower convex surface on said bolster end, sets of teeth arranged on an arc at each side of said convex surface, one of said sets of teeth being formed separately and secured to said bolster end.

24. In a bolster having an end arranged to extend into a window opening of a side frame, the combination of, a lower convex surface on said bolster end, spaced sets of teeth arranged at sides of said convex surface, one of said sets of teeth being formed separately and secured to said bolster end.

25. In a bolster having an end arranged to extend into a window opening of a side frame, the combination of, a lower convex surface on said bolster end curved transversely of said bolster, and means extending downwardly from said bolster end adjacent said convex surface for restricting independent movement of said bolster longitudinally of said side frame; said means being formed separately and secured to said bolster.

26. In a bolster having an end arranged to extend into a window opening of a side frame, the combination of, a lower convex surface on said bolster end curved transversely of said bolster, means operatively related to and extending

11

downwardly from said bolster end adjacent said convex surface; said means being formed separately and secured to said bolster, and hoods outstanding from side walls of said bolster end.

27. In a railway truck wherein a side frame is provided with a window opening defined by columns and a bolster end is positioned within the opening, the combination of, a spring supported chair within said opening and having vertically spaced flanges extending into said columns, friction means movable vertically by said chair flanges for frictionally engaging said columns, contacting arcuate surfaces of different radii on said bolster and chair for allowing said chair to rock longitudinally of said truck beneath said bolster, and means on said bolster and chair adjacent said arcuate surfaces for maintaining a predetermined relationship between said contacting arcuate surfaces.

28. In a railway truck wherein a side frame is provided with a window opening defined by columns and a bolster end is positioned within the opening, the combination of, a spring supported chair within said opening and having vertically spaced flanges extending into said columns, friction means movable vertically by said chair flanges for frictionally engaging said columns, contacting arcuate surfaces of different radii on said bolster and chair for allowing said chair to rock longitudinally of said truck beneath said bolster, and curved intermeshing teeth on said bolster and chair adjacent said arcuate surfaces for preventing said arcuate surfaces from angling horizontally relative to one another.

29. In a railway truck wherein a side frame is provided with a window opening defined by columns and a bolster end is positioned within the opening, the combination of, a spring supported chair within said opening and having vertically spaced flanges extending into said columns, friction means movable vertically by said chair flanges for frictionally engaging said columns, contacting arcuate surfaces of different radii on said bolster and chair for allowing said chair to rock longitudinally of said truck beneath said bolster, and curved intermeshing teeth on said bolster and chair adjacent said arcuate surfaces; some of said teeth on said bolster being formed separately and secured to said bolster.

12

30. In a railway truck wherein a side frame is provided with a window opening defined by columns and a bolster end is positioned within the opening, the combination of, a spring supported chair within said opening and having vertically spaced flanges extending into said columns, friction means movable vertically by said chair flanges for frictionally engaging said columns, contacting arcuate surfaces of different radii on said bolster and chair for allowing said chair to rock longitudinally of said truck beneath said bolster, intermeshing means on said bolster and chair for preventing said arcuate surfaces from angling horizontally relative to one another, and hoods outstanding from said bolster covering said friction means.

31. In a railway truck wherein a side frame has a window opening, the combination of a bolster member in said opening, a chair member supporting said bolster member, an arcuate surface on one of said members and contacting said other member for allowing said chair member to rock relatively longitudinally of said side frame, and means extending between said members adjacent said surface for maintaining a predetermined rocking contact therebetween.
